STREET LIGHTING FIXTURE

Myron F. Pettengill, Hendersonville, N.C., assignor to General Electric Company, a corporation of New York

Filed Aug. 19, 1965, Ser. No. 86,775

Term of patent 14 years

(Cl. D48—31)

The broken line showing in the disclosure is for illustrative purposes only.

I claim:

The ornamental design for a street lighting fixture, as shown and described.
